UNITED STATES PATENT OFFICE.

GOTTLOB WM. BEYERLE, OF SAN DIEGO, CALIFORNIA.

WIRE-FENCE LOCK.

No. 809,549.

Specification of Letters Patent.

Patented Jan. 9, 1906.

Application filed February 16, 1905. Serial No. 245,926.

To all whom it may concern:

Be it known that I, GOTTLÖB WM. BEYERLE, a citizen of the United States, residing at San Diego, in the county of San Diego and State of California, have invented a new and useful 5 Wire-Fence Lock, of which the following is a specification.

This invention relates to locks for connecting crossed wires, and has been particularly 10 designed for connecting the runner and stay wires of wire fences and is arranged to be conveniently applied to such wires at their points of crossing and then clamped upon the wires so as to rigidly interlock the same and 15 prevent slipping of either wire upon the other wire.

A further object of the invention is to have the lock complete in itself to facilitate its application to the wires and also capable of being 20 spread under pressure to draw the wires into intimate engagement and to grip the lock upon the wires.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made 25 within the scope of the claims without departing from the spirit or sacrificing any of the advantages of the invention.

In the accompanying drawings, Figure 1 is 30 a perspective view illustrating a pair of crossed wires connected by means of the present lock. Fig. 2 is a sectional view of the device as it is originally applied to the wires. Fig. 3 is a similar view after the lock has been 35 gripped upon the wires. Fig. 4 is an elevation looking at the spread ends of the lock. Fig. 5 is a detail perspective view of the lock prior to its application to the wires.

Like characters of reference designate corresponding parts in each and every figure of the drawings.

Referring at first more particularly to Fig. 5 of the drawings, it will be seen that the present lock is in the form of a substantially 40 U-shaped metallic clip 1, having its opposite sides pierced by corresponding openings 2, which vary in diameter according to the size of the wires to which the lock is to be applied. The extremities of the lock are beveled inwardly, as indicated at 3, so as to produce inwardly-converged terminals which

form an important part in the spreading of the lock, as will be hereinafter explained. At opposite edges of the back of the lock and midway between its sides are corresponding 45 wire-receiving seats, each seat being made up of a pair of spaced projections 4, extending toward the front of the lock and having their inner edges converged rearwardly.

In applying the present lock it is placed 50 astraddle of one of the wires of the fence, preferably the runner-wire 5, which is received within the seats formed by the projections 4, after which the stay-wire 6 is passed downwardly through the perforations 2, and 55 then some implement or object is placed against the beveled extremities of the lock and a blow or blows are struck against the back of the clip, thereby to spread the latter, as indicated in Fig. 3, and thus grip the sides 70 of the lock snugly upon the stay-wire, which is also bent or kinked, as at 7, by reason of the runner-wire being forced thereagainst, while at the same time the back of the lock is forced toward the fence and the runner-wire 80 5 is wedged between the beveled or converged sides of the two seats. The lock is held against horizontal sidewise movement by reason of the stay-wire passing through the perforations 2, and the lock is held 85 against vertical movement by reason of the runner-wire being received within the seats, wherefore the lock is effectually held against displacement. By the extremities of the lock being spread and its back forced 90 inwardly the crossed wires are drawn into snug engagement with one another, the extremities of the lock are gripped upon the stay-wire, and the runner-wire is wedged in the seats, thereby producing a strong and durable 95 interlocking connection between the two wires at their point of crossing.

It will here be explained that the sides or arms of the lock are separated by a space exceeding the diameter or thickness of the wire 100 to be spanned, and the wire-receiving seats 4 are carried by the back of the device independently of its arms, whereby when the arms are displaced from their parallel relation the seats still snugly receive the wire 5, 105 and thereby prevent looseness of said wire longitudinally of the wire 6 after the device has been secured in place.

From the foregoing description it will be understood that the present device is formed 110 from a single blank of metal and is entirely complete in itself, and therefore may be con-

veniently applied to the wires without bending the latter and is fixed in place by means of a blow or blows against the back of the lock in an exceedingly simple and expeditious manner.

Having fully described the invention, what is claimed is—

1. As a new article of manufacture, a lock for crossed wires comprising parallel arms separated by a space greater than the thickness of the member to be spanned and provided with alined openings exceeding the diameter of the member to be received therethrough, a back connecting the arms at one end of the device and the other ends of the arms being free and beveled, said arms capable of being bent at their connection with the back, and a seat carried by the back and opening in the direction of the open side of the lock.

2. A substantially U-shaped metallic lock for crossed wires having its arms separated by a space exceeding the diameter of the wire to be spanned and provided with alined openings exceeding the diameter of the wire to be received therethrough, the free ends of the arms being beveled upon their inner sides, and spaced projections carried by each edge of the back and extending toward the open side of the device, each pair of projections being spaced to snugly receive a wire, and the arms capable of being bent apart upon their connections with the back.

In testimony that I claim the foregoing as my own I have hereto affixed my signature in the presence of two witnesses.

GOTTLOB WM. BEYERLE.
